UNITED STATES PATENT OFFICE.

EDWIN GOMEZ, OF NEW YORK, N. Y.

IMPROVEMENT IN CARTRIDGES.

Specification forming part of Letters Patent No. 99,079, dated January 25, 1870.

To all whom it may concern:

Be it known that I, EDWIN GOMEZ, of the city and State of New York, have invented and made a new and useful Improvement in Firing Projectiles and Explosive Materials; and I do hereby declare the following to be a correct description of the same.

Heretofore the explosion of gunpowder in large quantities has been attended with loss of unconsumed powder, and the obtaining of but a small proportion of its effective force.

In other cases quick-firing material, such as in Letters Patent No. 18,199, granted September 15, 1857, and No. 86,980, granted February 16, 1869, has been employed, but at the risk of bursting the gun in which the same was fired, in consequence of the suddenness of the explosion.

My present invention has for its object the employment of a quick-firing powder, without the risk of injury to the gun, and so that the explosion follows up and accelerates the ball.

I will first describe the peculiarity of the means made use of, and then explain the operation.

In the drawing I have shown, in Figure 1, a longitudinal section of a projectile, and in Fig. 2 an elevation of the same.

a represents a ball of suitable size and shape. *b*, a central rod of wood or other light material, around which one or more coils of fuse are wound, as shown at *c*. This fuse is to be filled or made with quick-firing compound, such as in either of aforesaid patents, or acting like the same, and the case of said fuse may be of paper, folded up as in Letters Patent No. 34,057, granted January 7, 1862.

The rear end of the fuse is connected to a nipple, *d*, to receive a detonating-cap, or the said fuse may be fired in any convenient manner. The fuse being of powder within a folded case, is introduced into the nipple so as to expose the open end to the fire from the cap.

I have shown a cylinder, *e*, at the rear end of the rod *b*, said cylinder being formed with deep grooves running around the same like a screw, and into this the rear end of the fuse, or one coil of the same, is laid and passed to the nipple *d*, or other point of ignition.

The cartridge or projectile made in this man-

ner may be employed alone, although that is not my only object.

When fired in this manner in a smooth-bore gun, the action of the fuse in the grooves of the cylinder *e* is to give a rotary motion to the ball, rocket, or other projectile, and the direction in which the fuse *c* is wound is to correspond, with the same object in view. In this manner the projectile receives a rotary movement to aid the accuracy of the flight; and the fuse-powder, commencing to burn at the rear end, exerts its force in starting the ball, and the fuse is carried along with the ball, and, continuing to burn, increases the pressure of the gases and accelerates the velocity.

The area or space around the fuse is to be proportioned to the rapidity of the powder, for the risk of rupture of the gun will be prevented by allowing a space for the gases to act in starting the ball, and the length of the fuse is such that it will be consumed before the projectile leaves the cannon or gun, or before the propulsive force is required to cease. By this means the force exerted on the projectile will be greatest toward the last portion of the movement of the ball in the gun, thus greatly increasing its flight in proportion to the powder employed, and effectually preventing all the quick-firing powder going off in a mass, at the risk of injury to the gun.

The cylinder *e* and grooves aid in drawing or forcing out of the gun any pieces of the paper of the fuse.

The fuse inclosing the quick-firing powder in a tubular case, wound spirally or helically around the stem or support, is to be distinguished from the roll of paper and explosive material shown in Letters Patent No. 21,253, granted August 24, 1858.

One of the principal objects to be accomplished by this improvement is to fire gunpowder or other explosive material in the most advantageous manner to exert its force to the best advantage upon the material or article to be moved. This will be understood by reference to the drawing, wherein a case containing gunpowder is shown as surrounding the coil of fuse before described. In this instance, the action of the fuse and the gases evolved from the explosion will remain substantially

as before set forth, but the charge of powder surrounding the same will add its force to that of the powder of the fuse-coil, and these are to be regulated in their relative proportion and action to the desired work.

In firing gunpowder in this manner, there is an accumulation of pressure and effective force; thus the fuse, although burning with rapidity, is to be so proportioned in length as to continue to burn as the powder is progressively ignited; thus a comparatively small pressure is exerted as the ball starts, but the pressure accumulates with irresistible rapidity as the entire charge is ignited, and the fuse continues to convey the necessary fire of ignition until all the powder is burnt, the explosion not putting out the fuse or allowing any grains of the gunpowder to escape unconsumed, and I remark that this arrangement causes the ultimate force of the explosion to be directed upon the ball; but my extended tests lead me to know that if the explosion commenced next to the ball by my mode of firing and run back to the breech, the main force would be exerted there, and but comparatively little on the projectile, so that by arranging my coil accordingly, the force of the explosion can be directed to the bursting of cannon, or the performance of other similar work, under whatever condition, may be understood, and this peculiarity availed of; thereby a small amount of powder is rendered very powerful and efficacious, the accumulated force of the explosion being directed against the desired portion of the substances surrounding the powder-chamber.

I remark, further, that my experience leads me to know that in firing large charges of gunpowder, the pressure of the gases in the portion first exploded causes the powder to pack and the flame to be excluded.

In my improved method of firing the powder, the flame that sets the powder on fire penetrates the interstices in advance of any compressing action, so that all particles are consumed and lend their force in the explosion.

By my said invention, powder that may have become slightly damaged, or be of a finer grain than that usually employed for a

given purpose, or a second quality of powder may be used with success, as in all instances the fire of the fuse is in advance of the fire in the powder, the fuse being the quickest, and acting to ignite the powder, as aforesaid.

I have found that the noise of firing upon my improved plan is much lessened, and when a cartridge made as herein contemplated is used for blasting or in wells, the effect is intense; and in blasting the trembling of the surrounding rock is the principal indication that the explosion has taken place, but the effectiveness of the explosion is very much greater than in any modes of firing heretofore pursued.

To prevent any particles of the paper case of the coil of fuse remaining and smoldering, I prefer that the said paper be prepared with alum-water, and, when nitro-glycerine is employed, this coil may be coated with gutta-percha or similar material, to prevent the powder of the fuse becoming injured.

It will be apparent that by my mode of firing projectiles, the velocity being increased, a cannon or mortar of less weight can be employed to effect a given object, because the increased velocity of the projectile will make up for its less weight.

What I claim, and desire to secure by Letters Patent, is—

1. A projectile, having a rod, *b*, extending to the rear, in combination with a quick-firing fuse wound around said rod *b*, commencing near the ball, and fitted to be ignited at the rear end, so that the said fuse moves with the ball until it is entirely burnt, as and for the purposes set forth.

2. The cylinder *e*, with grooves receiving the fuse, in combination with the said fuse, applied in the manner and for the purposes substantially as set forth.

3. The folded fuse *c*, passing into the nipple *d* in the manner shown, so that the fire from the detonating cap-presses into the end of said fuse, as set forth.

Dated September 10, A. D. 1869.

Witnesses : EDWIN GOMEZ.
